AUTOMATIC CONTROL OF INTERNAL COMBUSTION ENGINES

Joseph Oberholzner, Jackson Heights, N. Y., assignor to Power Patents Company, Hillside, N. J., a corporation of Maine

Application August 30, 1939, Serial No. 292,566

5 Claims. (Cl. 123—97)

This invention relates generally to the control of internal combustion engines, and is more particularly directed to improvements in apparatus for effecting automatic deceleration control of internal combustion engine prime movers and of vehicles or other devices powered thereby.

The primary object of the invention is to provide apparatus which shall operate automatically in response to a drop in pressure in the intake manifold of an internal combustion engine below the normal idling intake pressure to retard or interrupt discharge of intake exhaust gases to atmosphere and to thereby build up a back pressure which is effective to reduce consumption of lubricating oil and to increase the gas compression resistance to the piston exhaust stroke during deceleration.

A more particular object of the invention is to provide an improved automatic deceleration control apparatus which is simple and economical both to install and to operate.

In the operation of internal combustion engines at idling speed, relatively high vacuum is developed in the intake manifold, and this vacuum is reduced during periods of acceleration. However, during periods of deceleration at engine speeds above the normal idling speed, a high degree of vacuum builds up in the intake manifold, and this high vacuum results in excessive consumption of lubricating oil, as well as in exhaust smoke and often back firing. A feature of the apparatus which is hereinafter described is that it embodies means for utilizing this high vacuum which is developed in the intake manifold during periods of deceleration at high speed, both to actuate a valve so mounted as to interrupt free discharge of engine exhaust gases to atmosphere, and also for initiating through sensitive pressure responsive mechanism the operation of the valve actuating means.

With the aforementioned and other objects and features in view, the invention consists in the improved apparatus for controlling internal combustion engine operation which is hereinafter described and more particularly defined in the accompanying claims.

The invention will be hereinafter described more specifically by reference to the accompanying drawing, which is a diagrammatic view in elevation, with parts shown in section, of a preferred embodiment of the improved deceleration control apparatus shown in operative relation with the intake and exhaust manifolds of an internal combustion engine.

55 Referring to the drawing, numeral 10 designates

the exhaust manifold and numeral 12 the intake manifold of an internal combustion engine with which the control apparatus of the present invention is operatively connected. Numeral 14 designates a poppet valve having a stem 15 which is slidably journaled in the longitudinal axis of manifold 10. A multi-apertured bearing support 16 for valve stem 15 is provided with a tubular extension 17 having at its top an inward taper forming an annular seat 18 for the valve 14. With the valve 14 in its normal open position (as illustrated) gas exhausted from the internal combustion engine flows through manifold 10 and through apertures 20 of the valve supporting member 16 in the direction indicated by the 15 arrows.

Reciprocal movement of the valve 14 toward and away from its seat 18 is produced by rotation of a cam 22 having its edge or operating surface mounted in aligned contact with the lower 20 end of valve stem 15. Cam 22 is keyed to a shaft 23, and a crank 24 is also keyed to shaft 23 at one end thereof. Actuating mechanism for the crank includes a piston 26 which is reciprocably mounted within a cylinder 28. The piston is connected 25 to the crank 24 by a piston rod 29 and a connecting rod 30. A retractile spring 32 is attached to connecting rod 30 in position to normally hold the crank, cam, piston and valve 14 in the position illustrated, allowing free discharge of engine 30 exhaust gases to atmosphere through the manifold 10.

For the purpose of actuating piston 26 in cylinder 28 a valve 34 is provided having a pair of fluid intake and exhaust ports, one of which is connected by a conduit 36 to the right hand end of cylinder 28 (as viewed in the drawing), while the other port of valve 34 is connected by a conduit 38 with intake manifold 12. When valve 34 is opened, communication is established between 40 cylinder 28 and the interior of manifold 12, and any vacuum which obtains in the manifold is applied to cylinder 28 and to piston 26 for the purpose of moving the piston toward the right hand end of the cylinder against the pull of spring 45 32. Movement of piston 26 toward the right under the pull of vacuum applied thereto serves to rotate cam 22 in clockwise direction to close valve 14, thereby interrupting discharge of engine exhaust gases to atmosphere and building up a 50 back pressure in the exhaust pipe 10 and in the engine cylinders (not shown) thereby retarding rotation of the engine crank-shaft.

An essential and important feature of the present invention is that of providing means which 55

shall be responsive to variations in vacuum within the intake manifold 12 within a narrow range, for controlling the operation of valve 34. It will be appreciated that mechanism such as the piston 26 and cylinder 28 for actuating valve 14 in the exhaust manifold, would not have sufficient sensitivity to be practically useful for limiting, within a narrow range of relatively high vacuum in the intake manifold, the periods during which discharge of engine exhaust gases to atmosphere shall be interrupted. Essentially the mechanism provided for controlling operation of valve 34 includes an adjustable flexible diaphragm unit 40 which is mounted within a casing and one side of which is communicably connected with the interior of manifold 12 by a pipe 42. To the other side of diaphragm 40 there is operatively connected a plunger 43 under the control of a retractile spring 44. The tension of spring 44 can be adjusted by a nut 45 threadably engaging plunger 43, so that the diaphragm will only operate in response to a vacuum which is somewhat greater than that developed in the intake manifold at idling speed, (for example a vacuum exceeding 19 inches of mercury). To the end of plunger 43 there is attached a stem 46 which is in turn connected to an end of a crank arm 47. Crank arm 47 is pivoted at its other end on a pin 48 which is supported by a bracket 49 mounted on the casing of valve 34. An actuating stem 50 for valve 34 is operatively connected to the crank arm 47 for reciprocal movement by the crank arm in response to any corresponding movement of the diaphragm 40.

35 When a vacuum is developed in the intake manifold 12 which exceeds by a predetermined amount the vacuum normally existing in the manifold during the period when the engine is operating at idling speed, diaphragm 40 moves 40 downwardly carrying therewith the unpivoted end of crank 47, and this movement effects corresponding downward movement of stem 50, causing valve 34 to open. As soon as valve 34 opens, communication is established between 45 manifold 12 and the interior of cylinder 28, causing piston 26 to move to the right to close valve 14.

When the vacuum in the intake manifold drops below that predetermined amount at which diaphragm 40 is adjusted to operate, the spring 44 will move the diaphragm and the free end of crank 47 upwardly sufficiently to close valve 34, thus interrupting communication between the cylinder 28 and the intake manifold, while at 55 the same time establishing communication between cylinder 28 and an air intake aperture 52 in the wall of valve 34. This communication is established through the lower chamber 54 of valve 34 and through a lateral port 56 and an axial bore 57 in the lower part of valve stem 50, which, with the valve in its closed position, brings an annular groove 58 in the valve stem in communicable relation respectively with bore 57 and with air intake aperture 52. Thus with valve 34 closed atmospheric air pressure is applied to the right hand end of piston 26, with the result that the retractile spring 32 is enabled to pull the piston 26 to the left hand end of cylinder 28, thereby bringing valve 14 to its normally open position 70 illustrated.

In order to prevent the development of too high back pressure within exhaust pipe 10 on the upstream side of valve 14 during the period when the valve is closed, a pressure relief valve 75 60 is provided which is adjustable by means of a

screw adjustment 62 to release excess pressure within the exhaust pipe whenever such pressure tends to exceed a predetermined safe value. The intake side of valve 60 is operatively connected to exhaust pipe 10 on the upstream side of valve 14, by a pipe 64; and the discharge side of valve 60 is operatively connected to the pipe 10 on the downstream side of valve 14 by a pipe 65.

If it be assumed, for example, that the control apparatus of the present invention is to be used with an engine which develops a maximum vacuum in the intake manifold of about 19 inches of mercury at idling speed, then the diaphragm 40 may be adjusted for opening valve 34 whenever the vacuum in the intake manifold 12 exceeds, for example, 19½ inches of mercury. Thus whenever the engine is operating at a speed above idling speed and is decelerating, the vacuum in the intake manifold increases above that at which the diaphragm 40 is set to actuate valve 34, thereby opening this valve and communicably connecting the intake manifold with the cylinder 28. Piston 26 is thus drawn to the right against the pull of spring 32, thereby closing the valve 14. This valve will remain closed as long as the engine is decelerating at a speed developing a vacuum above the idling vacuum in the intake manifold. When the vacuum in the intake manifold drops below that developed at idling speed, diaphragm 40 is moved upwardly under the action of spring 44, thereby closing valve 34 and at the same time opening communication between cylinder 28 and air aperture 52. Atmospheric pressure is thereby built up in chamber 28 at the right hand of piston 26, permitting spring 22 to move the piston toward the left to open valve 14.

Having thus described the preferred form of the invention, what is claimed as new is:

1. Control apparatus for internal combustion engines comprising, an exhaust discharge pipe for waste engine combustion gases, a valve mounted in said pipe for controlling discharge of gases therethrough to atmosphere, an intake pipe for delivering air and fuel to the engine, means operable by variations in gas pressure for actuating said valve, a conduit connecting said means with the intake pipe, a second valve in said conduit controlling communication between said valve actuating means and the intake pipe, a device operable by variations in gas pressure for actuating said second valve, and a conduit connecting said device with the intake pipe.

2. Apparatus as defined in claim 1 in which said device is adjustable for operation to open said valve only in response to a vacuum in said intake pipe greater than that existing therein when the engine is idling.

3. Apparatus as defined in claim 1 together with a pressure-relief valve having its intake operatively connected to the discharge pipe on the upstream side of the valve and having its exhaust side communicably connected with the exhaust pipe on the downstream side of the valve.

4. Control apparatus for internal combustion engines comprising, an exhaust discharge pipe for waste engine combustion gases, an apertured valve supporting and seating member mounted transversely in said exhaust pipe, a valve mounted on said member in position to completely interrupt discharge of engine exhaust gases to atmosphere when seated, an intake pipe for delivering air and fuel to the engine, means operable by variations in gas pressure for actuating said valve, a conduit connecting said means with the

- intake pipe, a second valve mounted in said conduit in position to control communication between said valve actuating means and the intake pipe, means operably associated with said second valve for establishing communication between the valve actuating means and atmosphere during periods when said second valve cuts off communication between the valve actuating means and the intake pipe, an adjustable gas pressure sensitive device for actuating said second valve, and a communicable connection between said device and the intake pipe.
5. Control apparatus for internal combustion engines comprising, an exhaust discharge pipe

for waste engine combustion gases, a valve mounted in said pipe for controlling discharge of gases therethrough to atmosphere, an intake pipe for delivering air and fuel to the engine, and means for actuating said valve, said means including an element normally holding said valve in open position, a device operable by variations in gas pressure, and a conduit connecting said device with the intake pipe, said device being adjustable for operation to effect closing of said valve only in response to a vacuum in said intake pipe greater than that existing therein when the engine is idling. 5
